UNITED STATES PATENT OFFICE

FRED C. EASTMAN, OF BEVERLY, MASSACHUSETTS, ASSIGNOR TO UNITED SHOE MANUFACTURING CORPORATION, OF PATERSON, NEW JERSEY, A CORPORATION OF NEW JERSEY

RETAINING MECHANISM

Original application filed February 20, 1930, Serial No. 430,048. Divided and this application filed July 27, 1931. Serial No. 553,328.

This invention relates to retaining mechanism, the present application being a division of a copending application for Letters Patent for improvements in machines for use in the manufacture of shoes, Serial No. 430,048, filed on February 20, 1930. The invention is herein illustrated as embodied in pawl and ratchet mechanism, although it is to be understood that in its more general aspects it is not limited to retaining mechanism of that particular character.

In machines of various kinds there is sometimes provided special mechanism, for example, pawl and ratchet mechanism, for retaining or holding a movable device or member in a position to which it is moved. An object of the present invention is to provide improved retaining mechanism which will operate with great precision and effectiveness, and more particularly, as applied to pawl and ratchet mechanism, to provide a construction such as to avoid back-lash between a pawl and the co-operating ratchet teeth. For the purpose in view the construction herein shown comprises pawl and ratchet mechanism having ratchet teeth that are movable relatively to the pawl with the member which is to be retained or held by the mechanism, together with means for moving the pawl lengthwise of the series of teeth to insure that it will be positioned in effective holding relation to one of the teeth. The means illustrated for thus moving the pawl comprises an eccentric which supports the pawl and is turned at the proper time to advance the pawl until it abuts against one of the teeth. Combined with the eccentric in the construction shown is also means for moving the pawl into and out of operative relation to the series of teeth. As illustrated, there are provided a plurality of pawls controlled as described and arranged in staggered relation to reduce the amount of movement that may be necessary to bring one of them into holding relation to the nearest

tooth, but it is to be understood that the invention is not limited to the use of a plurality of pawls. It will be further understood that the invention is not limited to a construction in which it is the ratchet teeth, as distinguished from the pawl or pawls, that are movable with the member controlled by the pawl and ratchet mechanism.

The novel features of the invention will now be more particularly described by reference to the accompanying drawings and thereafter pointed out in the claims, the invention being illustrated in the drawings as applied to a toe-lasting machine of a character more fully disclosed in the copending application of which this application is a division.

In the drawings,

Fig. 1 is a view showing partly in elevation and partly in section portions of the above-mentioned machine including the novel pawl and ratchet mechanism;

Fig. 2 is a perspective view illustrating in greater detail the means for controlling two of the pawls; and

Fig. 3 is a view similar to a portion of Fig. 1, showing one of the pawls in its idle position.

As more fully disclosed in the above-mentioned copending application, the machine includes in its organization wipers 10 for wiping the margin of the toe end of the shoe upper inwardly over an insole on a last, a toe band 12 for embracing the upper around the toe to assist in holding it, and upper-fastening mechanism comprising a member 14 which is movable to a position in front of the edges of the wipers 10, as illustrated in Fig. 1, for guiding fastenings driven through the upper and the insole. For positioning the last and shoe and supporting it against upward pressure there is provided an abutment member 16 having a plurality of pins 18, only one of which is shown in the drawings, which are arranged to project

through holes in the insole into sockets in the last. For maintaining the shoe and last in the position determined by these pins and for supporting it against pressure applied on its bottom face, there is provided a toe rest 20 having a pad 22 for engaging the shoe, this toe rest being mounted on the upper end of a rod 24 which is vertically movable in an upper fixed bearing 26 and 5 in a lower bearing 28 formed in a bracket 30 which is fast on the frame of the machine. Initially the toe rest 20 is in a lower position than indicated in the drawings to permit the last and shoe to be mounted on the pins 18, and in the operation of the machine it is 10 moved upwardly into supporting engagement with the shoe. For imparting such upward movement to the toe rest and its supporting rod 24, there is provided a sleeve 32 which is slidably movable on the rod 24 15 and acts through a spring 34 in engagement at its upper end with a collar 36 fast on the rod to raise the rod and force the toe rest 20 yieldingly against the shoe. The sleeve 32 bears at its upper end on a collar 38 slidably 20 mounted on a reduced portion of the rod 24 and engaging the lower end of the spring 34, this collar being arranged to engage a shoulder 40 on the rod when the parts are 25 in starting positions so that the spring 34 is at that time under a substantial amount of compression between the two collars 36 and 38. The sleeve 32 is connected by links 42, 30 only one of which is shown in the drawings, to the forked end of a lever 44 pivoted at 46 on the frame of the machine, and the other end of this lever is connected by a link 48 to a crank pin 50 carried by a gear wheel 52 which is fast on a power-operated shaft 54. 35 The shaft 54 is operated by a clutch-controlled mechanism, not shown in the drawings, whereby the shaft is turned through a half revolution at each actuation of the clutch. Accordingly, upon one actuation of the clutch, the toe rest 20 is moved upwardly 40 into supporting engagement with the shoe, and upon a second actuation of the clutch, after the lasting operations have been performed, it is lowered to its starting position. 45

50 In order to hold the last and shoe firmly up in the position determined by the pins 18, there is provided means for holding the rod 24 positively against any downward movement from the position to which it is raised 55 in forcing the toe rest against the shoe. For this purpose there is secured on the lower end portion of the rod a member 56 provided with a series of downwardly facing ratchet teeth 58 arranged to cooperate with a plurality of 60 detents or pawls 60 supported on the fixed bracket 30. The member 56 is mounted on a reduced portion of the rod 24 so that it bears at its upper end against a shoulder on the rod, and it is secured in place by set screws 62. In 65 the construction shown the pawls 60 are four

in number, arranged in upper and lower pairs, and they are also arranged in staggered relation so that in any position assumed by the rod 24 at the end of its movement to carry the toe rest into supporting engagement with 70 shoes of different sizes, some one of the pawls will be positioned in fairly close relation to the lower end face of one of the ratchet teeth 58. In order still further to insure against the possibility of any lost motion or backlash between the pawls and the ratchet teeth 75 such as to permit downward yield of the toe rest 20 when the pressure is applied on the bottom of the shoe, this invention provides means for controlling the pawls in such manner as to insure that one of them will be positioned in effective holding relation to one of the ratchet teeth to support the toe rest 80 against any downward movement. For this purpose the two pawls of each upper and lower pair are swivelled on an eccentric 85 which is part of a rock shaft 66 mounted in bearings in the bracket 30. Each of the two pawls is connected by a coiled spring 68 to one end of the head of a T-shaped pin 90 which is fast in the shaft 66 and projects through a slot 72 (Fig. 2) formed partly in the side of the hub of each pawl. The springs 68 thus serve as yielding connections through 95 which the pawls are swung toward and from the ratchet teeth 58 by turning movements of the shaft 66, and the slot 72 permits the shaft to turn relatively to the pawls after they have been swung into engagement with the ratchet teeth. Each of the shafts 66 is provided with 100 a crank arm 74, and the two crank arms are pivotally connected to a pair of links 76, so that the two shafts are turned in unison. The links 76 at their upper ends are pivotally connected to the lower end of a rod 78 which extends upwardly through a thimble 80 slidably movable on the rod, this thimble being loosely mounted in an opening formed in a plate 82 secured to an arm 84 which projects from the sleeve 32, and having on its upper end a flange 86 for engaging the plate 82. Between the thimble 80 and a collar 88 fast on the upper end of the rod 78 is a spring 90. Below the thimble 80 is a collar 92 which is 105 fast on the rod 78. 110

When the parts are in starting positions with the toe rest lowered and the sleeve 32 positioned as indicated in Fig. 3 and in dotted lines in Fig. 1, the thimble 80 rests upon the collar 92 with the spring 90 under some compression and the plate 82 is positioned considerably below the flange 86 on the upper end of the thimble. At that time the rod 78 is maintained by the plate 82 and the collar 92 in such a position that the pawls 60 are 115 swung outwardly away from the series of ratchet teeth 58, as indicated in Fig. 3, the pins 70 engaging the hubs of the pawls at the lower ends of the slots 72. When the sleeve 120 32 is moved upwardly by the shaft 54 to carry

the toe rest 20 into position to clamp the last against the pins 18, the plate 82 first slides upwardly along the thimble 80 without affecting the positions of the pawls 60. Substantially at the time when the spring 34 begins to yield in response to the upward movement of the sleeve 32, the plate 82 engages the flange 86 of the thimble 80 and acts through the spring 90 to lift the rod 78, thereby turning the rock shafts 66. As the shafts 66 are thus turned, the pawls 60 are swung into operative relation to the ratchet teeth through the yielding connections provided by the springs 68, the eccentrics 64 being turned with the shafts; and in the latter part of the turning movements of the shafts the eccentrics are carried to such positions that they impart to the pawls upward movements, lengthwise of the series of ratchet teeth 58, thus insuring that the pawl which is nearest to the lower face of a ratchet tooth will be carried into holding relation to the tooth to serve as an abutment to prevent any downward movement of the rod 24. In any further upward movement of the sleeve 32 that may take place after a pawl has thus been seated against a ratchet tooth the spring 90 yields, the thimble 80 being carried upwardly away from the collar 92, as indicated in Fig. 1. It will be understood that after one of the pawls has thus been seated firmly against one of the ratchet teeth, its controlling eccentric 64 is in such a position as to act as a substantially positive abutment to prevent any downward movement of the pawl in response to the pressure of the shoe on the toe rest 20. Insurance is thus afforded that the shoe will be maintained firmly in the position determined by the pins 18 and will be supported against any downward yield in response to the pressure applied on its bottom face in the overwiping and upper-fastening operations. It will be understood that in the return of the parts to starting positions the pawls 60 through the spring connections 68 are swung outwardly away from the ratchet teeth 58, so as to release the rod 24 for downward movement to carry the toe rest away from the shoe.

Having described the invention, what I claim as new and desire to secure by Letters Patent of the United States is:

1. In mechanism of the class described, the combination with a device movable from one position to another position, of means for holding said device in the position to which it is moved, said holding means comprising a member having a series of teeth thereon, a cooperating member arranged to act as a detent in abutting relation to some one of said teeth to hold the device, one of said members being movable with said device relatively to the other member, and means for effecting relative movement of said members in a direction lengthwise of said series of teeth after the movement of said device has

been substantially completed to insure a cooperative relation between the detent member and one of said teeth.

2. In mechanism of the class described, the combination with a device movable from one position to another position, of means for holding said device in the position to which it is moved, said holding means comprising a member having a series of teeth thereon, a cooperating member arranged to act as a detent in abutting relation to some one of said teeth to hold the device, one of said members being movable with said device relatively to the other member, and means for moving said other member in a direction lengthwise of the series of teeth after the movement of said device has been substantially completed to insure the positioning of the detent member in holding relation to one of said teeth.

3. In mechanism of the class described, the combination with a device movable from one position to another position, of means for holding said device in the position to which it is moved, said holding means comprising a member having a series of ratchet teeth thereon, a member arranged to act as a pawl in operative relation to said ratchet teeth, one of said members being movable with said device, and means for imparting to said pawl member movement in a direction lengthwise of the series of ratchet teeth after the movement of said device has been substantially completed to insure the positioning of the pawl member in holding relation to one of the teeth.

4. In mechanism of the class described, the combination with a device movable from one position to another position, of means for holding said device in the position to which it is moved, said holding means comprising a member movable with said device and having a series of ratchet teeth thereon, a pawl arranged to cooperate with some one of said teeth to hold the device, and means for moving the pawl in the same direction as said member after the movement of the member has been substantially completed to insure the positioning of the pawl in holding relation to one of the teeth.

5. In mechanism of the class described, the combination with a device movable from one position to another position, of means for holding said device in the position to which it is moved, said holding means comprising a member movable with said device and having a series of ratchet teeth thereon, a pawl arranged to cooperate with some one of said teeth to hold the device, an eccentric on which said pawl is mounted, and means for turning said eccentric to impart to the pawl movement in a direction lengthwise of said series of teeth after the movement of said device has been substantially completed to insure

the positioning of the pawl in holding relation to one of the teeth.

6. In mechanism of the class described, the combination with a device movable from one position to another position, of means for holding said device in the position to which it is moved, said holding means comprising a member movable with said device and having a series of ratchet teeth thereon, a pawl arranged to cooperate with some one of said teeth to hold the device, and means for moving the pawl into operative relation to the series of teeth and for also moving it in a direction lengthwise of the series of teeth to insure its holding relation to one of the teeth.

7. In retaining mechanism, the combination of a member provided with a series of teeth, a member arranged to act as a detent, in engagement with some one of said teeth, means for effecting relative movement of said members lengthwise of the series of teeth, and means for effecting a different relative movement of said members lengthwise of the series of teeth substantially at the end of said first relative movement to insure the positioning of the detent member in holding relation to one of the teeth.

8. In retaining mechanism, the combination of a member provided with a series of teeth, a detent arranged for holding engagement with some one of said teeth, means for moving said toothed member relatively to the detent in a direction lengthwise of the series of teeth, and means for imparting to the detent movement in a direction lengthwise of the series of teeth after the movement of said toothed member has been substantially completed to insure the positioning of the detent in holding relation to one of the teeth.

9. In retaining mechanism, the combination of a member provided with a series of ratchet teeth, a member arranged to act as a pawl in operative relation to the ratchet teeth, means for moving one of said members relatively to the other in a direction lengthwise of the series of teeth, and means for thereafter imparting to said pawl member a movement lengthwise of the series of teeth to insure its holding relation to one of the teeth.

10. In retaining mechanism, the combination of a member provided with a series of ratchet teeth, a pawl arranged to cooperate with said ratchet teeth, means for moving said member relatively to the pawl, and means for imparting to the pawl after the movement of said member has been substantially completed a movement in the same direction to insure its holding relation to one of the teeth.

11. In retaining mechanism, the combination of a member provided with a series of ratchet teeth, a pawl arranged to cooperate with said ratchet teeth, means for effecting relative movement of said member and

pawl in a direction lengthwise of the series of teeth, an eccentric on which the pawl is mounted, and means for turning said eccentric after said relative movement has been substantially completed to insure the positioning of the pawl in holding relation to one of the teeth.

12. In retaining mechanism, the combination of a member provided with a series of ratchet teeth, a pawl arranged to cooperate with said ratchet teeth, means for effecting relative movement of said member and pawl in a direction lengthwise of the series of teeth, and means arranged to operate after said relative movement has been substantially completed to move the pawl into operative relation to the ratchet teeth and also in a direction lengthwise of the series of teeth to insure its holding relation to one of the teeth.

13. In retaining mechanism, the combination of a member provided with a series of ratchet teeth, a pawl arranged to cooperate with said ratchet teeth, means for moving said member relatively to the pawl in a direction lengthwise of the series of teeth, a rotatable shaft, an eccentric carried by said shaft and on which the pawl is mounted, means also carried by the shaft for controlling the pawl to swing it into or out of operative relation to the teeth, and means for turning the shaft in automatically determined time relation to the movement of said ratchet member to swing the pawl toward the teeth and also to cause the eccentric to move it lengthwise of the series of teeth into holding relation to one of the teeth.

14. In pawl and ratchet mechanism, the combination of a series of ratchet teeth, a pawl arranged to cooperate with said ratchet teeth, a rotatable shaft provided with an eccentric on which the pawl is mounted, a spring controlled by said shaft for swinging the pawl yieldingly into engagement with the ratchet teeth as the shaft is turned, and means for turning the shaft to swing the pawl into engagement with the teeth and to cause the eccentric to move it lengthwise of the series of teeth.

15. In pawl and ratchet mechanism, the combination of a series of ratchet teeth, a pawl arranged to cooperate with said ratchet teeth, a rotatable shaft provided with an eccentric on which the pawl is swiveled, means carried by said shaft for imparting to the pawl swinging movement about the eccentric into or out of operative relation to the ratchet teeth, and means for turning said shaft to swing the pawl toward the ratchet teeth and to cause the eccentric to move it lengthwise of the series of teeth.

16. In pawl and ratchet mechanism, the combination of a series of ratchet teeth, a pawl arranged to cooperate with said ratchet teeth, a rotatable shaft provided with an

eccentric on which the pawl is swiveled, a member projecting from the shaft, a spring connecting said member to the pawl for swinging the pawl into or out of operative relation to the ratchet teeth as the shaft is turned, and means for turning the shaft to swing the pawl toward the ratchet teeth and also to cause said eccentric to move it lengthwise of the series of teeth.

10 In testimony whereof I have signed my name to this specification.

FRED C. EASTMAN.
